DESIGN FOR A BRACKET FOR AN ILLUMINATING DEVICE

John A. Korengold, Chicago, Ill.

Application April 12, 1937, Serial No. 68,689

Term of patent 7 years

To all whom it may concern:

Be it known that I, John A. Korengold, a citizen of the United States, residing at the city of Chicago, county of Cook, State of Illinois, have invented a new, original, and ornamental Design for a Bracket for an Illuminating Device, of which the following is a specification, reference being made to the accompanying drawing, forming a part thereof, in which Figure 1 is a side

elevation view, Figure 2 is a plan view, and Figure 3 is a reverse side elevational view of a bracket for an illuminating device embodying my design.

I claim—

The ornamental design for a bracket for an illuminating device, substantially as shown.

JOHN A. KORENGOLD.
